UNITED STATES PATENT OFFICE.

JOHN E. MUHLFELD, OF SCARSDALE, AND GEORGE W. CLENDON, OF BROOKLYN, NEW YORK, ASSIGNEES TO ECONOMY DEVICES CORPORATION, OF NEW YORK, N. Y., A CORPORATION OF NEW YORK.

STEAM VALVE-CHEST.

1,261,953.

Specification of Letters Patent. Patented Apr. 9, 1918.

Original application filed September 7, 1915, Serial No. 49,184. Divided and this application filed July 11, 1916. Serial No. 108,576.

To all whom it may concern:

Be it known that we, JOHN E. MUHLFELD, of Scarsdale, county of New York, and State of New York, and GEORGE W. CLENDON, of the borough of Brooklyn, county of Queens, State of New York, have invented certain new and useful Improvements in Steam Valve-Chests, of which the following is a specification.

10 This invention relates to steam valve chests and particularly to the valve chests of locomotives, and it is a division of our application, Serial Number 49,184, filed September 7th, 1915, for safety aperture closure.

15 One of the primary objects of our invention is to provide a simple and economical arrangement of valve chest having improved means whereby ready access may be had to the valve parts in the interior of the chest.

20 Another of the objects of our invention consists in utilizing certain of the standard parts of the valve chest as a safety means for retaining certain of the valve chest parts in position in the event of failure of the

25 normal fastening means. Our invention further contemplates a novel arrangement of detachable end-plate for the valve chest, the advantages of which will hereinafter be set forth. In addition, our invention com-

30 prises the provision of an improved end-plate for the valve chest whereby the joint between the plate and the valve chest may be located back of means used to removably connect the valve chest to the cyl-

35 inder, and also the utilization of such means as a safety device, preventing the plate from blowing off of the valve chest in the event of the failure of the means for detachably securing the plate to the chest.

40 The foregoing, together with such other objects as may hereinafter appear, or are incident to our invention, we obtain by means of a construction, a preferred embodiment of which we have listed in the accom-

45 panying drawings wherein:

Figure 1 is a longitudinal section through a steam engine valve chest embodying our invention; Fig. 2 is a front end elevation of Fig. 1; Fig. 3 is a sectional detail taken

50 on the line III-III of Fig. 1; Fig. 4 is a front end elevation of a valve chest embodying a modification of our invention; Fig. 5 is a section taken on the line V-V

of Fig. 4; and Fig. 6 is a detailed section of still another modification of our invention.

Referring particularly to Figs. 1 and 2, it will be seen that we have shown a portion of the cylinder 1 of a locomotive, which cylinder is provided with a flat valve face 1^a having induction and eduction port openings 2-2, intermediate which is an exhaust port opening 3. The induction and eduction port openings 2-2 form the terminals of the induction and eduction ports 2^a which lead to opposite ends of the cylinder 1. The port opening 3 is a terminal of the exhaust port 3^a which communicates with an exhaust pipe (not shown). A segmental or D-shaped valve chamber 4, open at the ends, is detachably secured to the valve face by any preferred means, there being interposed between the valve face and the valve chamber a plurality of gaskets 6, which may be of any preferred type, but which are shown in the drawings in the form of joint wires. Removably mounted in the valve chamber 4 is an open-ended, suitably ported, cylindrical bushing 7 in which the piston distribution valve reciprocates. This piston valve comprises two cylindrical heads 8-8 provided with suitable packing rings and an intermediate spool 8^a, the heads and spool being rigidly connected by means of the bolt 8^b. The stem for operating the valve is indicated by the numeral 9. Inclosing the valve mechanism is a valve chest 10 which is preferably cast integral and which is detachably secured to the cylinder 1 by means of a plurality of studs 11 and nuts 11^a, a suitable gasket 10^a being interposed between the valve chest and the valve chest seat formed on the cylinder. The valve chest mechanism just described is what is known as the universal valve chest by means of which it is possible to substitute for the ordinary slide valve mechanism, a piston type distribution valve, without the substitution of new parts. It will be understood, however, that our invention is equally well applicable to other forms of standard valve chests.

Heretofore it has been the customary practice to cast the valve chest as an integral unit, and although peep-holes have been provided therein, the valve chest was usu-

ally so constructed that it was necessary to remove it bodily from the cylinder when it was desired to replace or adjust any of the valve parts located therein. We propose to provide an opening in the valve chest of a size sufficient to remove the valve parts for purposes of repair or replacement and to close such opening with our improved end-plate or cover. With this in view, the valve chest 10 is provided at its forward end with an aperture or opening 12 having a shoulder 12^a. The end-plate preferably comprises a cylindrical member 13 having a flange 13^a and a shoulder or offset portion 13^b corresponding to the shoulder 12^a in the opening 12. The gasket 13^c, preferably of joint wire, is interposed between the shoulders 12^a and 13^b, and the end-plate is detachably secured in position by means of a plurality of studs 14 and nuts 14^a. Formed in the cylindrical portion of the end-plate are vertical holes 15 (see Figs. 1 and 3) preferably two in number, such holes being arranged so that a pair of the studs 11, by means of which the valve chest 10 is detachably secured to the cylinder 1, may be passed therethrough.

This construction forms a simple, convenient and inexpensive arrangement whereby the end-plate is prevented from blowing off of the valve chest in the event that the studs 14 or the nuts 14^a fail. It will thus be seen that the studs 11 which pass through the end-plate perform a double function, namely, they have their normal function of securing the valve chest 10 to the cylinder 1, and they form a safety retaining means for the end-plate. Thus while the end-plate is readily removable for purposes of assembly, inspection, repair or adjustment, no additional parts are required to secure these additional advantages.

Inasmuch as the end-plate must have movement relative to the safety holding means, in order that a tight joint between the end-plate and the valve chest may at all times be secured, the diameter of the holes 15 is made larger than that of the studs 11 which pass therethrough. In order to prevent leakage through the openings 15 and around the studs 11, the aperture 12 and the end-plate are so formed that the shoulders 12^a and 13^b are located to the rear of the studs 11; that is to say, the joint for the closure is located between the safety holding means and the pressure cavity of the valve chest proper. It will be seen that by this improved construction a steam tight joint for the end-plate is secured while at the same time the safety means is so arranged that the nuts 14^a may be freely drawn up from time to time to tighten the joint, as may be required. As hereinbefore pointed out, the arrangement is simple, effective and inexpensive and requires but a minimum

number of parts while at the same time the gasket or other packing means employed may be readily renewed.

In the modification shown in Figs. 4 and 5 the arrangement of valve chest is substantially the same but differs from that previously described in that the aperture or opening 12 in the valve chest and the end-plate 13 are of rectangular shape, the end-plate being provided with a plurality of slots 15^a instead of holes 15 as shown in the construction of Figs. 1, 2 and 3. These slots extend rearwardly from the front face of the end-plate to a point approximately adjacent the rear wall of the end-plate and it will be readily seen that the slots permit movement of the end-plate relative to the studs 11 so that the joint may be tightened whenever necessary.

In the construction shown in Fig. 6, the opening 12 in the valve chest 10 is tapered and threaded and the end-plate 13 is in the form of a tapered threaded plug having a squared end 16. A single hole 17 is formed in the plug for the reception of a stud 11, which in this case acts not only as a safety element but also as a means for preventing the plug from turning loose.

We claim:

1. The combination in a steam engine valve chest having an orifice, of bolts for detachably securing said valve chest to the engine cylinder, an end-plate for said orifice, and means for detachably securing said end-plate in position, the said end-plate being so arranged relative to the valve chest that the attaching bolts for said valve chest serve as safety retaining means in the event of failure of the means for detachably securing the closure member in position.

2. The combination in a steam engine valve chest having an orifice, of means for detachably fastening the valve chest to the engine cylinder, and an end-plate for said orifice, certain of the means for detachably securing the valve chest to the engine cylinder being located outside of the inner face of the end-plate thereby serving as a retaining means therefor.

3. The combination in a steam engine valve chest having an orifice, of means for detachably securing the valve chest to the engine cylinder, a closure member for said orifice, certain of said fastening means being located outside of the inner face of the said closure to act as a retaining means therefor, and a packing between the valve chest and said closure located intermediate the said fastening means and the pressure chamber of the valve chest.

4. The combination in a steam engine valve chest having an orifice, of means for detachably securing the valve chest to the engine cylinder, a closure member for said orifice, and means for detachably securing

said closure member to the valve chest, a part of said means for detachably fastening the valve chest to the engine cylinder having coöperative relation with the closure member to retain the same in position in the event of the failure of the means for detachably fastening the closure member to the valve chest.

5. The combination in a steam engine valve chest having an orifice, of means for detachably fastening the valve chest to the engine cylinder, a closure member for said orifice, certain of said fastening means having a lost motion connection with said closure member, and means for adjusting the position of the closure member with reference to the valve chest.

6. The combination in a steam engine valve chest having an orifice, of an adjustable closure member for said orifice, and means for detachably securing said valve chest to the engine cylinder, certain of said fastening means coöperating with said closure member to act as a safety retaining means therefor.

7. The combination in a steam engine valve chest having an orifice, of a closure member for said orifice, means for detach-

ably securing said closure member to the valve chest, and means for detachably fastening the valve chest to the engine cylinder having coöperative relation with the closure member to retain the same in position in the event of the failure of the means for detachably fastening the closure member to the valve chest.

8. The combination in a steam engine valve chest having an orifice, of a closure member for said orifice, means for detachably securing said closure member to the valve chest, means for detachably fastening the valve chest to the engine cylinder having coöperative relation with the closure member to retain the same in position in the event of the failure of the means for detachably fastening the closure member to the valve chest, and a packing for said closure member located intermediate the pressure chamber of the valve chest and the means for detachably fastening the valve chest to the engine cylinder.

In testimony whereof we have hereunto signed our names.

JOHN E. MUHLFELD.
GEORGE W. CLENDON.
